Attorney:

UNITED STATES PATENT OFFICE.

STEPHEN J. CLULEE, OF ATTLEBORO, MASSACHUSETTS.

TAG.

1,275,226.

Specification of Letters Patent. Patented Aug. 13, 1918.

Application filed March 4, 1918. Serial No. 220,276.

To all whom it may concern:

Be it known that I, STEPHEN J. CLULEE, a citizen of the United States, residing at Attleboro, in the county of Bristol and State of Massachusetts, have invented certain new and useful Improvements in Tags, of which the following is a specification.

My invention relates to that type of tags adapted for attachment to ophthalmic 10 mountings, rings, and other small articles.

The essential objects of my invention are to afford in a small tag a maximum of space 15 utilizable for printed matter; and to attain this end in a light, reliable, and inexpensive structure capable of facile attachment and detachment.

To the above end my invention consists in such parts and combinations of parts as fall within the scope of the appended claims.

20 In the accompanying drawings which form a part of this specification.

Figures 1 and 2 are plan views of the outside and inside of my tag in extended position.

25 Fig. 3, a side view of the same,

Figs. 4 and 5, front and rear elevations respectively of the tag in engaged position, and

Fig. 6, a side view of the same.

30 Like reference characters indicate like parts throughout the views.

My tag is composed preferably of paper, parchment, prepared linen, or similar flexible tag material, and comprises in a single 35 piece enlarged tablet or display tabs A and B connected by strap or neck C. The member A has display faces a and a' on its outer and inner faces respectively; and the member B has similar faces b and b' analogously disposed respectively. In the present instance the member A is rectangular and the member B is circular, and the former is of greater length than the latter, in order that, in the attached or engaged position of the tag, the members A and B afford less opportunity for mutually obscuring each other's inner faces, and facilitate manual sepa-

ration if accidentally forced into contact with each other. The four faces a, a', b, and b' are adapted to receive written or printed matter. For example one face may contain the seller's trade mark; another, his guarantee; another, the number of the article; and the fourth, the quality mark or other matter.

It is essential that all four faces of the tag be available for display, and to insure this, the attaching member for forming and preserving the final attaching loop is applied at the end of the strap C. The attaching member, indicated in a general way by D, consists of a metal spangle or clamp comprising a circular body or plate d provided with four peripheral bendable tongues or prongs, two of which d', d', diametrically opposite each other, engage the edges of the neck C and are clamped thereover; while the two remaining prongs d², d², are passed through the strap adjacent the member A or through perforations e. In bending the tag into attachable form the strap C is folded around the article to be identified and the prongs d² are passed through the end of the strap adjacent the member B or through perforations f so located, and adapted, when the neck is folded, to register with the perforations e. After the prong d² have been clamped down as shown in Figs. 5 and 6, the four display faces a, a', b, and b' are available. Heretofore only two faces of the tag have been available for display faces. To increase the accessibility of the display faces the members A and B are caused to diverge from each other by bending the strap C at points, such as at g, adjacent the members A and B; but such bending is not essential, since the inner faces of the members A and B carry no adhesive, hence the observer can obviously manually separate the members without effort.

I claim:—

1. As an article of manufacture, a marking tag comprising non adhesive display tabs and a strap connecting the tabs, and means adjacent the tabs for engaging the

- ends of the strap to each other to form a loop.
2. As an article of manufacture, a marking tag comprising a strap, display tabs integral with both ends of the strap and disengaged from each other, and a member engaging the strap adjacent the tabs to form an engaging loop.

3. As an article of manufacture, a marking tag comprising a strap, tabs on both ends of the straps provided with four display faces, and a clamping member engaging the strap at points adjacent the tabs. 10

In testimony whereof I have affixed my signature.

STEPHEN J. CLULEE.
